UNITED STATES PATENT OFFICE.

JAMES T. LAWLESS, OF TOLEDO, OHIO.

STORM-CURTAIN FOR CARRIAGE-TOPS.

SPECIFICATION forming part of Letters Patent No. 617,294, dated January 3, 1899.

Application filed March 21, 1898. Serial No. 674,640. (No model.)

To all whom it may concern:

Be it known that I, JAMES T. LAWLESS, of Toledo, county of Lucas, and State of Ohio, have invented certain new and useful Improvements in Storm-Curtains for Carriage-Tops; and I do hereby declare that the following is a full, clear, and exact description of the invention, which will enable others skilled in the art to which it appertains to make and use the same, reference being had to the accompanying drawings, and to the numerals of reference marked thereon, which form part of this specification.

My invention relates to a storm-curtain for carriage-tops, and has for its object to provide an attachable and detachable curtain for a carriage-top, whereby the entire front of the carriage may be closed on the occasion of inclement weather, or the curtain may be detached from the top in fair weather or swung upon its axis and secured within the top of the carriage for causes of emergency.

The invention is designed for attachment to carriages of present use or constructed so as to be made an element of those of future construction.

In the drawings, Figure 1 is a front elevation of a carriage-top provided with my improved curtain. Fig. 2 is a side elevation. Fig. 3 is an elevation of the frame of the storm-curtain, showing the lower transverse bar attached thereto. Fig. 4 is a sectional detail showing the front carriage-top bow in section with a clamp secured thereon having an eye to receive the bent end of the lower transverse bar. Fig. 5 is an elevation of the same. Fig. 6 is a preferred form of hook for attaching the lower transverse bar to the storm-curtain frame. Fig. 7 is an elevation of a screw-hook for suspending the storm-curtain to the transverse portion of the front carriage-bow, showing the frame of the storm-curtain in section.

1 designates the carriage-top bow, and 2 the top of the carriage-top. From the front bow of the carriage-top there is suspended the frame of the storm-curtain 3 by means of hooks 4, which engage with the transverse front bow of the carriage, preferably by being screwed therein, and are provided with hook portions

5, into which is entered the upper transverse bar 6 of the curtain-frame, having integral with the bar a plurality of rods 8 8, preferably four. To lend rigidity, rods 8 8 are connected with a lower curved transverse bar 9, 55 extending across the width of the front of the carriage, and to this framework is secured a covering of fabric, leather, or any desired material, and there may be a plurality of panes of glass 10 secured therein to allow the occupant 60 of the carriage to look outwardly. Transverse bar 9 is connected to the front carriage-bow by means of clamps 11, which embrace the bow, and each clamp is provided with an eye 12 to receive the bent ends 13 of the bar 65 9, preferably formed with a keyhole 14, into which may be inserted a key, and upon the bar 9 may be arranged a plurality of hooks 15, the eyes of which are run upon the bar 9, and the upper end of the hook engaged with 70 the transverse bar 16 of the frame. Provision is made for securing a lap-robe 17 to the bar 9 by engaging the lap-robe with buttons 18 upon the bar 9, thereby entirely deflecting the water received upon the storm-curtain to 75 the lap-robe or rubber blanket, which may be used, and intermediate the joinder of the storm-curtain and lap-robe the reins 19 may be passed. It will be seen that by this arrangement the entire curtain may be readily 80 detached from the carriage-top by withdrawing the curved ends 13 from the eyes 12 of the clamps 11 and disengaging the curtain-frame from the hooks and that it may also be as readily attached to the carriage-top. 85

The fabric or covering material of the storm-curtain is of a width to be provided with buttonholes and receive buttons 20 arranged upon the carriage-bow. Should it be desired to retain the storm-curtain 3 within the carriage-top, the ends 13 of the bar 9 are disengaged from the eyes 12 of the clamps 11 and the entire curtain may be swung in the arc of a circle, as shown in dotted lines, Fig. 2, and the bar 9 secured to the carriage-bow frame 90 in the top of the carriage-top by hooks 21.

By this arrangement a carriage of present construction may be readily equipped with my improved storm-curtain by means of the hooks 4 and clamps 11, and its convenience 95 100

of attachment and detachment, as well as that of retention within the carriage-top frame, is one of essential value in this branch of the art.

What I claim is—

- 5 1. In a storm-curtain for carriage-tops, a metal framework of an area to close the front of the carriage, having an upper horizontal bar provided with hooks to engage the framework of the carriage-top, a lower bar with 10 downwardly-projecting ends, and clamps to embrace the carriage-bows, having openings to receive the projecting ends of the lower bar.
- 15 2. In a storm-curtain for carriage-tops, a metal framework having a suitable covering and transparent panes, means for suspending the frame detachably to the carriage-top, a curved lower bar, means for detachably se-

curing the same to the front carriage-bows, and hooks upon the lower curved bar for engaging the lap-robe.

3. A storm-curtain for carriage-tops comprising a rectangular frame of a width to swing within the carriage-top, a suitable covering arranged upon the frame, screw-hooks 25 secured in the front carriage-bow from which the frame is suspended, and hooks within the carriage-top to secure the storm-curtain within the top.

In testimony that I claim the foregoing as 30 my own I hereby affix my signature in presence of two witnesses.

JAMES T. LAWLESS.
